UNITED STATES PATENT OFFICE

EVERETT H. KNEEN, OF ANSONIA, CONNECTICUT

CONTAINER FOR ADHESIVE PLASTER AND THE LIKE

Application filed September 30, 1931. Serial No. 566,011.

This invention relates to improvement in containers for adhesive plaster and the like, and particularly to containers comprising a ring and a spool with flanges adapted to enter either end of the ring, the object of the invention being a simple construction which provides means for locking the spool in the ring, and the invention consists in the construction and arrangement of parts as will 10 be hereinafter described and particularly recited in the claim.

In the accompanying drawing:

Fig. 1 is a plan view of a container for adhesive plaster and similar material constructed in accordance with my invention;

Fig. 2 is a side view of the same;

Fig. 3 is a sectional view on the line 3—3 enlarged;

Fig. 4 is a sectional view on the line 4—4 of Fig. 3; and

Fig. 5 is a perspective view of the ring detached.

In carrying out my invention, I employ a ring 10 formed from a strip of metal with 25 the edges at each end rolled outward to form beads 11 and 12. In each bead, at a plurality of points, the bead is struck inward so as to form slight bumps 13 at one end and corresponding bumps 14 at the other end. The 30 spool is of usual construction, comprising a core 15 and ends 16 and 17 secured thereto in the usual manner, and the length of the spool is slightly less than the length of the ring. The edges of the ends are rolled to 35 form beads 18 and 19, the diameter of the ends being very slightly less than the diameter of the ring.

A spool thus formed may be entered into the end of the ring, and the entering-end 40 17 will spring past the bumps 13 and come to a bearing against the bumps 14; at the same time, the end 16 will pass and be held by the bumps 13.

This construction permits the spool to be 45 entered or removed from either end of the ring and be held in the ring with sufficient friction to prevent accidental removal.

I claim:

50 A container for adhesive plaster and similar material, comprising a ring, the ends of

the ring rolled outwardly forming a bead and each bead formed with a plurality of inwardly-extending bumps, a spool having ends of a diameter slightly less than the diameter of the ring and adapted to spring 55 past the said bumps, whereby the spool is interlocked with the ring.

In testimony whereof, I have signed this specification.
